UNITED STATES PATENT OFFICE.

WILLIS G. YOUNG, OF CHICAGO, ILLINOIS.

DESIGN FOR A GAME-BOARD.

51,623.

Specification for Design.

Patented Dec. 18, 1917.

Application filed October 27, 1917. Serial No. 198,874. Term of patent 7 years.

To all whom it may concern:

Be it known that I, WILLIS G. YOUNG, a citizen of the United States, residing at Chicago, in the county of Cook and the State of Illinois, have invented a new, original, and ornamental Design for a Game-Board, of which the following is a specification, reference being had to the accompanying drawing, forming part thereof.

The figure is a plan view of a game board showing my new design.

I claim:

The ornamental design for a game-board as shown.

WILLIS G. YOUNG.

Witnesses:

HARRIET FANSELOW,
CHAS. KAUFFMANN.
